(57) **CLAIM**

The ornamental design for furniture, as shown and
described.

DESCRIPTION

FIG. 1 is a front view of furniture showing my new design;
FIG. 2 is a right-side view thereof, the left-side view being
a mirror image view thereof; and,

FIG. 3 is a top view thereof.

The broken line showing in the drawings is for illustrative
purposes only and forms no part of the claimed design.
